UNITED STATES PATENT OFFICE.

ERNEST FRIEDRICK, OF THE UNITED STATES NAVY.

RANGE AND DEFLECTION TRANSMITTER.

1,116,407.

Specification of Letters Patent. Patented Nov. 10, 1914.

Application filed September 3, 1913. Serial No. 787,940.

To all whom it may concern:

Be it known that I, ERNEST FRIEDRICK, lieutenant, United States Navy, at present attached to the U. S. S. Arkansas, and a citizen

5 of the United States, have invented certain new and useful Improvements in Range and Deflection Transmitters; and I do hereby declare the following to be a full, clear, and exact description of the invention, such 10 as will enable others skilled in the art to which it appertains to make and use the same.

This invention relates to an apparatus for visually indicating data at a distant station, and is especially adapted for use on war vessels in connection with range and deflection transmitters, sight setters, gun pointing means, etc., and it has for its object to produce a mechanism which will accurately and rapidly communicate data from a gun fire control station to the plotting room and from the plotting room to the sight setters at the guns, or elsewhere, if it should be desired.

25 With this and other objects in view, the invention consists in the novel details of construction and combinations of parts, more fully hereinafter disclosed and particularly pointed out in the claims.

30 Referring to the accompanying drawings forming a part of this specification in which like numerals designate like parts in all the views:—Figure 1 is a diagrammatic view of a transmitting and receiving station equipped 35 with my invention; Fig. 2, is a diagram of the wiring at the transmitting station between the operating motor and the range or deflection indicating means; Fig. 3, is a diagrammatic view of the wiring between

40 the commutator at the transmitting station, and the follow up motor at the receiving station; Fig. 4, is a sectional plan view taken on the line 4—4 of Fig. 5, illustrating the range indicating means at the transmitting station; Fig. 5, is a sectional elevational view of the parts shown in Fig. 4, taken on the line 5—5 in that figure; Fig. 6, is a cross sectional view taken on the line 6—6 of Fig. 5; Fig. 7 is a cross sectional plan

45 view of the commutator taken on the line 7—7 of Fig. 8; Fig. 8 is a cross section in elevation taken on the line 8—8 in Fig. 7; Fig. 9 is a cross section in plan taken on the line 9—9 in Fig. 12; Fig. 10, is a detail of 50 a pawl shown in Fig. 12; Fig. 11, is a plan

view partly in section of the range drums at the receiving station; and Fig. 12 is a sectional view taken on the line 12—12 in Fig. 11.

The range indicating means 1, at the transmitting station, is connected to an operating motor 2 by the shaft 3, and said motor is also connected with the commutator 4, by the shaft 5, as will be clear from Fig. 1. The shaft 3, see Fig. 4, is provided with a worm 6, meshing with the gear 7, mounted on the standard 8 and said gear 7 carries the contact or stop member 9 as well as the contact ring 10, with which the contact or brush 9 is connected as shown in Figs. 2 and 5. The ring 10 is by means of the brush 11 connected with the holder 12 mounted on the standard 8 and said holder is joined by the wire 13 to the connection or cable 14 as shown. Also mounted on the standard 8 is the range plate 15, provided with the range scale 16, observable through the opening 17 in the cover plate 18. Also mounted on the standard 8 and secured to the plate 15 as by screws shown is the worm gear 19 engaging the worm 20, carried by the shaft 21, provided at one end with the cross handles 22 and at its other end with the crank 23. The crank handle 23 can be conveniently operated by hand when making large changes in the range, while the cross handles 22 are more convenient when making small changes in the range. The range plate 15 also carries two conductor rings 24 and 25 with which the brushes 26 and 27 respectively engage, and which brushes are joined by the wires 28 and 29 to the cable 14 as shown. The cable or connection 14 is composed of the wires 13, 28 and 29 which are joined with the reversible operating motor 2, as best shown in Figs. 1 and 2, and the stop contact or brush 9 makes the circuit through the reversing half ring conductors 36 or 37, separated by the space 35 according to the position of the range plate as will presently appear. The reversing ring 36 is joined to the ring 25, by the brush connection 39, and the reversing ring 37 is joined to the ring 24 by the brush connection 40 as diagrammatically shown in Figs. 2 and 5. It will now be clear from what has been so far disclosed that any desired range may be made to appear in the opening 17 by manually operating the handles 22 and 23 to change the range already appearing at

80

the sight opening 17. But as the plate 15 is thus turned it will of course carry with it the half ring conductors 36 and 37, and the brush 9 on the gear 7 will make circuit with 5 the one or the other of these reversing contacts, thus turning on the current automatically to the motor 2 in the proper direction. That is to say, contact with one member, say 36, will increase the range already 10 shown, while contact with the other member, say 37, will decrease it, or vice versa, and then the motor moves the gear 7 carrying the contact 9 in the proper direction to cause it to come to the open space 35, which is only 15 slightly wider than the said contact 9, when the motor will automatically stop, leaving the plate 15 indicating the change it was desired to make in the former range.

42 represents any suitable well known automatic electric brake, coacting with the shaft 3, and held free from said shaft only when current is passing through its magnets, so that the commutator 4, now to be described, will not be rotated after the stop 20 contact 9 reaches its neutral position at 35 and after current is therefore cut off. Such brakes are usually provided with spring members which grip the shaft instantly when current is cut off, and thereby stop all 25 rotation. The commutator 4, operated by the other end 5 of the shaft 3, see Figs. 1, 7 and 8, is mounted on a standard 45, carrying the worm gear 46, engaging the worm 47 carried by said end 5 or commutator operating 30 shaft. Also mounted on said standard 45 and moving with said worm gear 46 are the individual eight commutator segments 48, 49, 50, 51, 52, 53, 54, and 55, as best shown in Fig. 3. Opposite segments are 35 also preferably cross connected as shown. That is to say, segments 51 and 55 are connected by the wire 56, joined to the ring 57; segments 50 and 54 are connected by the wire 58 joined to the ring 59; segments 49 and 53 are connected by the wire 60 joined to the ring 61, and segments 48 and 52 are connected by the wire 62 joined to the ring 63. Contacting with the rings 59, 57, 63, and 61, are respectively the brushes 64, 65, 66 and 67, and connected with these said 45 brushes respectively are the wires 68, 69, 70 and 71 all as will be clear from Fig. 3. A wire 72 leads from brush 73 adapted to successively contact with all the segments 48 to 55. The said commutator 4 controls the receiving, or what I call a follow up motor 75 as follows: Said motor is provided with eight poles corresponding to the eight segments 48 to 55 of the commutator, opposite 50 poles being connected in pairs as follows:— Poles 76 and 77 are joined by the wire 78 and excited over the commutator wire 68; poles 79 and 80 are joined by the wire 81 and fed from the commutator wire 69; poles 82 and 83 are joined by the wire 84 and fed

from the commutator wire 70; and poles 85 and 86 are joined by the wire 87 and fed from the commutator wire 71. A common return wire 88 leads to the battery or other source of current 89, which connects with 70 the said wire 72 and brush 73 as shown.

90 represents an armature mounted on the shaft 91 adapted to take up a position between any pair of poles that might be excited from the commutator. The said shaft 75 91 is provided with a pinion 92 meshing with the internal gear 93 mounted on the range drum 94, provided with the numerals 95, see Figs. 11 and 12.

Associated with the first range drum 94, 80 is a second range drum 96, both being mounted on the shaft 97, carrying the disk 98, having the cutaway portion 99, into which moves the roller member 100 carried by the sliding yoke 101, upon each revolution of said shaft 97 and first drum 94. The said yoke 101 is slotted as at 102 to receive the supporting pin 103 carried by said first drum 94, and a spring 104 constantly urges its extreme head or end 105 radially outward toward the periphery of said second drum 96. This said periphery is provided on its interior with the slotted teeth or projections 107, adapted to be engaged by the reduced portion 108 of said head 105, whenever the cutaway portion 99 and member 100 are in register. Accordingly whenever the roller 100 enters the notch or cut away portion 99, the tooth 107 engages a tooth 107 on the drum 96 and causes said drum to 100 move with the drum 94 until said roller 100 leaves said notch 99. The angle subtended by the notch corresponds to one range division on the drum 96, and therefore one rotation of the drum 94 turns the drum 96 105 through one division.

The operation of my invention will be clear from the foregoing, but may be summarized as follows:—The range plate 15 is, through the handles 22 or 23 set to indicate 110 zero, or some other quantity such as the approximate range, and the same quantity or range is made to appear at all the receiving stations by the automatic turning of the operating shaft 91 by means of the follow 115 up motor 75, which is controlled by the commutator 4, governed by the motor 2. The parts are also so adjusted that the stop contact 9 will be normally opposite the space 35, so the circuit through the motor 2 will be 120 normally open. The accurate range is next determined and the plate 15 is by the handle 23 brought quickly to indicate the said range or approximately the same if the change is large, and it may be brought with 125 greater accuracy to indicate the exact range by moving said plate by means of the handles 22, when the change is small. The movement of the plate 15 and the contacts 36 and 37 by means of the gears 19 and 20, 130

and the movement of the gear 7 and contact 9 by means of the motor 2 constitute an important feature of my invention, for in some of the transmitters now in use such contacts 5 are made by hand levers, and in actual use owing to nervousness, excitement, etc., such levers are thrown too far or not far enough, thus making uncertain contacts and rendering the receiving instruments unreliable.

10 My improvements, however, obviate these objections. Current being thus automatically turned on, the gear 7 as well as the commutator shaft 5 will be turned by means of said motor until the stop contact 9 again reaches the space 35 when the motor will automatically stop. In the meantime the shaft 5 has rotated the commutator segments 48, 49, etc., past the brush 73, through 15 an angle precisely the same, or strictly proportional if gearing is interposed, to the angle traversed by the armature of the motor 2. The turning of these said commutator segments causes such poles in the follow up or receiving motor 75, to be energized 20 as will compel its armature 90 to traverse precisely the same arc as did the commutator segments, or as did the armature of the said motor 2. It therefore follows, that the follow up motor shaft 91 will rotate the first 25 range drum 94 either the same angular distance that the motor 2 rotates the gear 7, or some proportion or multiple thereof, according to the gear connection employed. I prefer to use the reducing gear connections 92, 30 93 illustrated, and so proportion the same that each complete rotation of the pinion 92 will turn the drum 94 through one indication, in this instance denoting fifty yards, since the first or unit column is stationary 35 and does not move. I further prefer to so proportion the parts that a complete rotation of the drum 94 on its shaft 97 will move the second drum 96 through one indication, in this instance a thousand yards, and while 40 45 I have shown a specific carrying mechanism for this purpose, yet any other suitable means may be employed.

By the means so far disclosed, ranges and other data up to any amount may be transmitted according to the capacity of the indicating drums, and the latter can be made, by well known means, of any capacity desired.

Should it be desired to transmit deflections to the right or left of the target, a precisely similar mechanism may be employed, and if both deflections and ranges are to be transmitted, the indicating drums will be correspondingly changed, or else independent drums be employed.

The foregoing mechanism will also be found useful in transmitting intelligence of various kinds. In fact, with slight changes it may be converted into a range deflection

transmitter, and it can be with somewhat 65 greater changes converted into a sight setter.

It is obvious that those skilled in the art may vary the details of construction as well as the arrangement of parts without departing from the spirit of my invention, 70 and therefore I do not wish to be limited to the above disclosure except as may be required by the claims.

What I claim is:—

1. In a range transmitter the combination 75 of a range indicating means; a motor geared to said indicating means; a commutator controlled by said motor; a second motor located at a distant station connected to and controlled by said commutator; and a range 80 indicating means geared to said second motor, substantially as described.

2. In a range transmitter the combination 85 of a range indicating means comprising a rotatable range indicating plate; means comprising a gear for turning said plate to indicate the desired range; a motor geared to said indicating means; a commutator controlled by said motor; a second motor located at a distant station connected to and 90 controlled by said commutator; and a range indicating means geared to said second motor, substantially as described.

3. In a range transmitter the combination 95 of a range indicating means comprising a rotatable range indicating plate; means comprising a gear for turning said plate to indicate the desired range; contacts controlled by said plate; a motor geared to said indicating means; connections between said contacts and said motor; a commutator controlled by said motor; a second motor located at a distant station connected to and controlled by said commutator; and a range 100 indicating means geared to said second motor, substantially as described. 105

4. In a range transmitter the combination 110 of a range indicator comprising a range indicating plate; contact members carried by said plate; gear means for rotating said plate to indicate the desired range; a motor electrically connected to said contact members; a gear carrying a single contact adapted to close circuit with said contact members; and an operative connection between said motor and said gear, substantially as described.

5. In a range transmitter the combination 120 of a range indicator comprising a range indicating plate; contact members carried by said plate; gear means for rotating said plate to indicate the desired range; a motor electrically connected to said contact members; a gear carrying a single contact adapted to close circuit with said contact members; an operative connection between said motor and said gear; a commutator controlled by said motor; and a receiving 125

mechanism at a distant station controlled by said commutator, substantially as described.

6. In a range transmitter the combination of a range indicator comprising a range indicating plate; contact members carried by said plate; gear means for rotating said plate to indicate the desired range; a motor electrically connected to said contact members; a gear carrying a single contact adapted to close circuit with said contact members; an operative connection between said motor and said gear; a commutator controlled by said motor; a second motor at a distant station controlled by said commutator; and indicating drums driven by said second motor, substantially as described.

7. In a range transmitter the combination of a range indicating means; a motor geared to said indicating means; an automatic brake adapted to stop the motion of said motor when current is cut off; a commutator controlled by said motor; a second motor located at a distant station connected to and controlled by said commutator; and a range indicating means geared to said second motor, substantially as described.

8. In a range transmitter the combination of a range indicating means comprising a range indicating plate having two half ring contacts with a space between them and a gear plate having a contact adapted to make circuit with said half ring contacts, one at a

time; a motor in circuit with said contacts; an automatic brake adapted to stop the motions of said motor when said circuit is broken; a gear connection between said motor and said gear plate; and means controlled by said motor for indicating at a distant station the angular movements of said range indicating plate, substantially as described.

9. In a range transmitter the combination of a range indicating means comprising a range indicating plate having two half ring contacts with a space between them, and a gear plate having a contact adapted to make circuit with said half ring contacts, one at a time; a motor in circuit with said contacts; an automatic brake adapted to stop the motions of said motor when said circuit is broken; a gear connection between said motor and said gear plate; and means comprising a commutator, a second motor and a range indicating mechanism controlled by said motor for indicating at a distant station the angular movements of said range indicating plate, substantially as described.

In testimony whereof I affix my signature, in presence of two witnesses.

ERNEST FRIEDRICK.
